UNITED STATES PATENT OFFICE.

HORACE L. McCURDY, OF DETROIT, MICHIGAN.

CARBURETER.

1,159,851.

Specification of Letters Patent.

Patented Nov. 9, 1915.

Application filed May 17, 1915. Serial No. 28,505.

To all whom it may concern:

Be it known that I, HORACE L. McCURDY, a citizen of the United States, residing at Detroit, in the county of Wayne and State of Michigan, have invented a new and useful Carbureter, of which the following is a specification.

This invention relates to carbureters for internal combustion engines, and its object is to produce a device of this character which shall be simple in construction, which can be sold at a low price, and which shall provide the proper explosive mixture irrespective of the speed of the engine to which it is attached.

This invention consists in the details of construction illustrated in the accompanying drawings, described in the specification and particularly pointed out in the claims.

In the accompanying drawings, Figure 1 is a vertical central section of this improved carbureter. Fig. 2 is an elevation of the same, showing the air inlet. Fig. 3 is a plan on the line 3—3 of Fig. 1. Fig. 4 is a vertical central section of a modified form of carbureter. Fig. 5 is an elevation of the upper end thereof. Fig. 6 is a section through the valve chamber. Fig. 7 is a perspective view of the throttle valve.

Similar reference characters refer to like parts throughout the several views.

The body of the carbureter shown in Figs. 1, 2 and 3 may be formed with flanges 1 at its upper end to secure it to the intake passage of an internal combustion engine. Just below the flanges 1 is a cylindrical valve chamber 2, whose lower end is closed by means of a diaphragm or head 3. Extending down from the head 3 is a cylindrical float chamber 4, to which the head 5 is secured in any desired manner, preferably by screw threads. Connected to the hub 6 of the head 5 is a fitting 7 having a threaded opening 8, into which the ordinary fuel supply pipe may be screwed, and also provided with a drain cock 9. Mounted within this fitting 7 is shown a screen or filter 11, which may be of any desired character.

The float 13 is shown mounted on the stem 14, which stem is slideable at its upper end in a central hole in a hub 15 on the head 3, and at its lower end in the head 5. A valve 16 is formed on the lower end of the stem 14, or secured thereto in any desired manner. A small tubular plug 17 in the

lower end of the bore 18 of the hub 6 permits the fuel to flow up this bore 18, but at the same time prevents the float from falling a sufficient distance to remove the upper end of the stem 14 entirely from the bore in 60 the hub 15.

The annular space around the outside of the chamber 4 and constituting a fuel chamber, connects with the interior thereof by means of any desired number of holes 19. 65 Flanges 22 and 23 support the tube 24, preferably of glass, around the body 4 in such manner that the fuel may flow out through the small openings 19 into the fuel chamber between this body 4 and the tubular shell 70 24. The interior of the float chamber may connect with the exterior air by means of a passage 20.

A series of openings 26 are formed in the head 3, as indicated in Figs. 1 and 3, to permit the flow of fuel into the valve chamber from the fuel chamber between the walls 4 and 24. Mounted within the valve chamber is a throttle valve consisting of a circular plate 29 and a cylindrical flange 30 formed with an opening 32 whose upper edge is inclined, as shown in Fig. 2. The plate 29 has a notch 31 as shown in Fig. 3. Secured to the plate 29 is an arm 33, by means of which this throttle valve may be turned, and extending out through an opening 34 in the chamber 2. It will be seen that as this disk 29 is swung by means of the arm 33, that the openings 26 may be covered or uncovered as desired. It will also be seen that, because of the inclined upper wall of the opening 32, the amount of air which may pass in through the openings 32 and 34 will depend entirely upon the position of the arm 33, and that as this arm is swung to the left in Fig. 2, the amount of air which may pass through the opening 32 will be cut down and the change will be greater than the reduction of the fuel supply because of the closing of the openings 26. 100

The operation of the device is simple. When the throttle valve is entirely open, as shown in Fig. 2, all of the openings 26 will be open. As the opening 32 is always of less area than the chamber 2, a considerable suction will occur at the upper ends of the passages 26. This will cause the fuel to pass through the openings 19 and rise in the annular fuel chamber between the body 4 and the shell 24. The float will fall in the 110

float chamber because of the opening 20 permitting the air to rush in. After the float has descended the proper distance, the valve 16 will be moved off its seat and fuel will 5 flow up through the bore 18 in the hub 6 and into the float chamber and out through the passages 19 to the fuel chamber and passages 26. By swinging around the arm 33 the number of these passages 26, and therefore 10 the flow of fuel may be reduced or increased, and such change will always be less than the reduction or increase in area of the passage 32.

The spring 36 presses down the plate 29 15 against the head 3 and is in turn held down by means of the washer 37 and the pin 38, as shown in Fig. 1. The fuel vapor or gas passes out through the upper end of the fuel chamber:

20 Instead of controlling the flow of the fuel to the holes 26 by means of a float, this structure may be simplified in the manner shown in Figs. 4 to 7 inclusive. The fuel pipe may be connected to either of the branches of the 25 T 40 and the drain cock 41 may then screw into another, depending upon whether the carbureter is to be horizontal or vertical. A hub 42 of the fuel chamber 43 screws into a third branch of this fitting, being provided 30 with a filter or screen 44 as previously described.

The body of the carbureter extends beyond the fuel chamber 43 to form a cylindrical valve chamber 44 and a carbureting or mixing chamber 45, the latter provided with 35 perforated lugs 46 whereby the carbureter may be secured to the intake passage of the engine. Separating the fuel chamber and the valve chamber is a head 47 having 40 central hubs 48 and 49 in which the valve stem 50 is slidable. At the lower end of the stem 50 is a fuel-valve 52 in the form of a double cone, a lower cone to close the passage 53 in the hub 42, and an upper cone 5 to close the space around the stem 50 when the valve 52 is at the upper limit of its movement. A light spring 54 on the hub 49 holds the fuel-valve on its lower seat when the engine is at rest.

50 Mounted on the hub 48 is a throttle valve having a bottom plate 55, two segmental flanges 56 and an operating arm 57. The head 47 is provided with two series of fuel apertures 58 which are arranged circumferentially of the hub 48 so that they may discharge through the notches 59 in the plate 55. As the valve is turned, these apertures are closed or opened as previously described.

55 Instead of the wall of the carbureter being formed with a rectangular air inlet opening and the valve with a triangular opening, as shown in Figs. 1, 2 and 3, the valve chamber 44 is formed with triangular air inlet apertures 61 which may be closed

by means of the segments 56, this construction being the equivalent of the other. As in the carbureter first described, the air aperture will be reduced in greater proportion than the reduction of the fuel supply, 70 thus providing a greater proportionate supply of fuel for small throttle opening than for great.

A positive control of the air inlet apertures 61 may be desirable to provide for 75 changes in air conditions due to differences in barometric pressures. A sleeve 63 may be mounted on the valve chamber 44 and have triangular apertures 64 similar to the apertures 61 in the valve chamber and slots 80 65 to receive the screws 66 on which this sleeve is mounted. An arm 67 may be employed to revolve the sleeve on the valve chamber to reduce or enlarge the air inlet of this carbureter.

To open the fuel passage, an air valve 70 may be employed, and may be mounted within the upper end of the valve chamber 85 on the stem 50, being normally held against the shoulder 71 on this stem by means of 90 the spring 72 and washer 73.

The operation of this carbureter is as follows. When the engine is at rest, the valve 52 is held seated by the spring 54 and the valve 70 is positioned to nearly close the upper end of the valve chamber. When the engine is being started, the suction will lift the air valve 70 and with it the fuel-valve 52, permitting fuel to flow from the passage 53 into the fuel chamber and thence, through 100 the apertures 58 to the valve chamber. As the rush of air increases, the air valve may be lifted still farther, the fuel-valve however stopping when it engages the lower end of the hub 49.

105 To hold the throttle valve against the head 67, a spring 75 may be mounted on the hub 48 between the valve and the collar 76. Many changes may be made in the details of the constructions shown without departing 110 from the spirit of the invention as set forth in the claims.

I claim:

1. In a carbureter, the combination of a cylindrical float chamber having heads at its upper and lower ends, a cylindrical shell surrounding said chamber and forming a fluid-tight joint with said heads to constitute a fuel chamber, said float chamber being formed with passages connecting the fuel chamber with the interior of the float chamber, the upper head having passages extending from said fuel chamber, a valve chamber connected to said upper head and having an air passage through its wall, a cylindrical 115 throttle valve fitting within said valve chamber and provided with an air passage and with an arm by means of which it may be swung to gradually close the fuel passages in said head and said air passage, one of said 120

125 130

air passages being triangular, a float within said float chamber, and means to feed fuel to said float chamber.

2. In a carbureter, the combination of a cylindrical float chamber and a valve chamber in alinement with each other, a head separating the chambers, an annular fuel chamber connecting to the lower end of the float chamber and extending up to said head 10 which is formed with small passages through which the fuel may flow to the valve chamber, said valve chamber having an air inlet opening and an outlet opening, and a cylindrical throttle valve fitting within the valve 15 chamber and provided with an opening in its cylindrical wall adapted to register with the air inlet, said valve being adapted to be moved to gradually close the air inlet opening and consecutively close the fuel passages 20 at the same time.
3. In a carbureter, the combination of a float chamber, an upper head therefor, a cylindrical valve chamber mounted on said head and having an air inlet in its wall, said 25 head having small fuel passages opening to the valve chamber, a fuel chamber connecting to the float chamber and to said fuel passages in said head, and a throttle valve mounted and fitting within the valve chamber 30 and comprising a circular disk having a notch to uncover the fuel passages in said head, a cylindrical flange formed with a triangular air passage, and an arm by means of which the valve may be turned to close 35 said air and fuel passage.
4. In a carbureter, the combination of a fuel chamber, a head therefor, a cylindrical valve chamber mounted on said head and

having an air inlet in its wall, said head having small fuel passages opening to the valve 40 chamber, means to convey fuel to said fuel chamber, and a throttle valve mounted in the valve chamber comprising a circular disk having a notch to uncover the fuel passages in said head, a cylindrical flange formed with an air passage, and an arm by means of which the valve may be turned to close said air and fuel passage, one of said air passages being triangular said fuel passages in the head being adjacent to the air inlet in 50 the wall of the valve chamber so that the incoming air will immediately come into contact with the fuel, said cylindrical part of the valve fitting against the wall of the valve chamber. 55

5. In a carbureter, the combination of a fuel chamber and means to feed fuel thereto, a cylindrical valve chamber above the fuel chamber and provided with an air inlet in its wall, a head separating the 60 two chambers, and a valve revolubly mounted in the valve chamber on said head and comprising a cylindrical portion fitting within the cylindrical valve chamber and having an opening adapted to register with the air 65 inlet, and a disk fitting against said head and having a cut away portion adjacent the air opening, said head being formed to permit the flow of fuel from the fuel chamber to the valve chamber and said valve being so 70 mounted as to restrict said flow at a greater rate than the restriction of the air through the air inlet.

In testimony whereof I have signed this specification.

HORACE L. McCURDY.
